APPARATUS FOR APPLYING LININGS TO
SHOE SOLESMaury P. Medwick, Brooklyn, and Marvin Fox,
New York, N. Y.

Application March 21, 1939, Serial No. 263,126

13 Claims. (Cl. 12—20)

This invention relates to a device adapted for use in the manufacture of shoes, and more particularly for the application of the so-called "sock-lining" on and around the edge of an insole. It is also probably useful for other purposes as will be apparent from the description appearing hereinafter.

The sock-lining of a shoe is usually a thin layer of sheet material, such as textile fabric, leather, simulated leather or the like, which in the shoe is in direct contact with the foot or stocking worn by the wearer. In the construction of the shoe, the sock-lining is adhesively attached to the upper face of an insole and the marginal edge of the sock-lining is folded about the edge of the insole and adhesively attached to the under face of the insole. The apparatus to which the present invention relates is one in which is performed the steps of folding the marginal edge of the sock-lining around the edge of the insole and adhesively securing the infolded edge of the sock-lining to the under face of the insole. The object of the present invention is to provide a mechanism for speedily and effectively performing the steps just mentioned in a manner not heretofore contemplated whereby the shoe construction is not only improved, but the manufacturing cost considerably reduced.

In the accompanying drawing, wherein several embodiments of the invention are shown, Fig. 1 is a face view of an insole and attached sock-lining, such as is operated upon by the device constituting the invention; Fig. 2 is a side elevation of the device with parts of the same in longitudinal section, the section being taken on the line 2—2 of Fig. 3, looking in the direction of the arrows; Fig. 3 is a plan view of the device with the plunger means omitted, and parts broken away and other parts in section, to disclose construction; Fig. 4 is a fragmentary sectional view showing the device in its compressed position in the act of folding down the marginal edge portion of the sock-lining over the insole; Fig. 5 is a sectional view on the line 5—5 of Fig. 3, looking in the direction of the arrows; Fig. 6 is a sectional view of a modified structure; Fig. 7 is a similar sectional view showing the device of Fig. 6 in its compressed position in the act of pressing down the infolded marginal edge portion of the sock-lining over the insole; and Fig. 8 is a perspective view of one of the pressing elements shown in Fig. 7.

The character of the article upon which the improved apparatus is adapted to operate is indicated in Fig. 1, where it will be seen that the

same consists of what is known in the shoe manufacture as an "insole" 1, the same being usually composed of cardboard or the like, and adapted to have one of its faces covered by a so-called "sock-lining" 2. The sock-lining 2 is, in the finished shoe, that layer of material located within the shoe and in direct contact with the foot or stocking of the wearer.

In the construction of the shoe, the sock-lining is adapted to have its marginal edge portion 3 shown projecting beyond the edge of the insole, folded around the edge of the insole 1 and adhesively secured to the bottom face thereof, indicated at 4. The present invention therefore, relates to an apparatus which folds the marginal edge portion 3 of the sock-lining over the edge of the sole 1 and adhesively attaches the folded over marginal edge 3 to the bottom face 4 of the sole. The structure of the invention simultaneously folds down and adhesively attaches the entire marginal edge portion of the sock-lining to the face 4 of the sole.

In Figs. 2 to 5 of the drawing inclusive, a plate or similar element is shown at 5, the same being provided with an opening or aperture 6 of a shape 10 to permit the passage through it of the sole 1. The opening 6, upon the passage of the sole 1 through it, causes the marginal edge 3 of the sock-lining to be folded to an upstanding position, as clearly shown in Fig. 5. Any suitable 15 means may be employed for forcing the sole 1 and attached sock-lining down through the opening 6 to bring it to rest upon a pivoted foot-shaped element or supporting base member 7 forming a part of a plate or similar member 8, 20 located below, and spaced from, the upper apertured plate member 5. Extending between and connecting plates 5 and 8 is a wall provided by a plurality of closely positioned articulated members 9, the construction of which is more clearly 25 shown in Fig. 5. These members consist of a plurality of links 10 hinged together at 11 and respectively hinged to the plates 5 and 8 at 12. These articulated members 9 are placed in close 30 relationship so that they co-operate in the formation of a substantially continuous wall, shaped to conform to the aperture 6, so that when the sole 1 and attached sock-lining 2 is forced down through the aperture 6, the upstanding marginal 35 edge portion 3 of the sock-lining will be maintained in such upstanding position by being enclosed by said wall until the sole and attached sock-lining comes to rest upon the pivoted support 7. The plates 5 and 8 are normally held 40 in spaced-apart relationship by means of springs 45

13 or other resilient elements which tend to also hold the articulated links 9 in their vertically disposed position, clearly shown in Figs. 2 and 5. When the sole and sock-lining comes to rest upon the pivoted support 7, plate 5 is then forced downwardly toward plate 8 causing the articulated members to fold or collapse inwardly on their pivots 11 and 12 to thereby press downwardly against the then upstanding marginal edge portion 3 of the sock-lining and fold it down flatwise against the bottom face 4 of the insole. Since the entire sole is surrounded by the wall, composed of the articulated members 9, it will be apparent that when said wall collapses inwardly as above explained, it will fold down simultaneously the entire marginal edge portion 3 of the sock-lining to cause it to overlie the face 4 of the sole and be adhesively secured thereto. It is of course, understood that the marginal edge portion 3 of the sock-lining is coated with an adhesive to permit of such adhesive attachment.

The means for thrusting the sole and attached sock-lining through the opening 6 in the plate 5 and also for causing the plate 5 to be moved toward the plate 8 to bring about the inward folding or collapse of the articulated members 9 is clearly shown in Fig. 2. It will be there seen that such means includes a plate 14 which may be shaped similarly to the opening 6 but of a smaller size, said plate being mounted on the ends of studs 15 which extend through an upper plate 16, the studs being surrounded by coil springs 17 holding the respective plates 14 and 15 apart as shown in Fig. 2. Studs 15 are provided with heads 18 to limit movement of plate 14 away from plate 16. Plate 16 is attached to a vertical shaft 19 which forms a part of any suitable plunger-operating mechanism and is vertically reciprocable either by manual operation or by a suitable mechanical means.

In the operation of the device, sole 1 and attached sock-lining 3 are placed as a unit over the opening 6 in plate 5 with the upper face of the sock-lining facing downwardly as shown in Fig. 2 and its marginal edge portion 13 preventing it and the attached sole from falling downward through the opening 6. The plunger upon its descent brings its lower plate 14 into contact with the sole 1 and forces it downwardly through the openings 6, finally bringing it to rest upon the pivoted supporting member 7. The effect of this downward movement of the sole and attached sock-lining is to cause the marginal edge portion 3 of the sock-lining to be folded upwardly to an upstanding position by its engagement with the edge of the aperture 6 and with the vertical wall formed of the articulated members 9. Thus, when the sole and sock-lining reaches a position of rest on the upper face of the supporting member 7, it is in the position shown in Fig. 5. When the plate 14 reaches a position of rest upon the supporting member 7, the plate 16 continues its further downward movement against the pressure of the springs 17 and said plate 16 being larger than the opening 6 in plate 5, it strikes the upper surface of the plate 5 and moves the same downwardly against the pressure of the springs 13. As plate 5 is moved downwardly toward the plate 8, the wall composed of the articulated members 9 is collapsed or buckled inwardly as clearly shown in Fig. 4, so that said wall forces the upstanding marginal edge portion 3 of the sock-lining downwardly and inwardly over the bottom face 4 of the sole, causing said folded down portion of the sock-lining

to be adhesively secured to the face 4 of the insole. When this has been done, the plunger rises to its elevated position shown in Fig. 3 to be positioned in readiness for the insertion of the next sole and attached sock-lining.

The supporting member 7 conforms in shape to the aperture 6 and it consists of a plate pivoted at 20 at its opposite ends and provided with a weight 21 at one side of a longitudinal line connecting the pivots, said weight tending to normally maintain the supporting member 7 in an inclined position as indicated in dotted lines in Fig. 5. The descent of the plunger thrusting a sole and sock-lining down with it will tend to cause the pivoted supporting plate 7 to swing upwardly to the position shown in full lines in Figs. 2 and 5, in which position it will be held as long as the pressure of the plate 14 holds a sole and attached sock-lining on it. As soon as the plunger rises at the completion of the operation of folding down the sock-lining, the pivoted support 7 will assume its tilted or inclined position under the influence of the weight 21, and permit the completed sock-lining and sole to slide downwardly from its upper surface by gravity to a suitably placed receptacle. The pivoted support 7 is provided with one or more suitable stops 22 to limit its upward pivotal motion under pressure of the plate 14.

In the embodiment of the invention shown in Figs. 6 to 8 inclusive, the collapsible wall extending between and connecting the plates 5 and 8 is composed of a plurality of annular elastic elements such as indicated at 23. These elements may be made of rubber or suitable elastic material and be placed adjacent one another in a manner similar to the articulated members 9. When the plate 5 is moved toward the base plate 8 in the manner heretofore described, the tubular elastic members 23 will be collapsed as shown in Fig. 7, causing the portion of the same which faces inwardly to overlie and press downwardly the marginal edge portion 3 of the sock-lining over the sole. To prevent lateral shifting of the upper plate with regard to the lower plate, guide pins 24 are provided, said pins surrounding the compression springs 13.

From the foregoing, it will be obvious that with the structures disclosed, insoles and attached sock-linings may be speedily fed to a position above the opening 6 and upon the descent of the plunger, the marginal edge portion 3 of each sock-lining may be folded over and down upon the sole and adhesively attached thereto. The entire folding down of the marginal edge of the sock-lining occurs simultaneously so that the work is very rapid, efficient and uniform. If desired, devices of this construction may be arranged in a gang, so that a number of soles may be fed and operated upon simultaneously. These and other modifications may be made in the structure without departing from the scope of the annexed claims.

What we claim is:

1. In an apparatus of the character described, a member provided with an opening through which a sole and attached sock-lining is adapted to be thrust, a base portion spaced from said member and adapted to receive the sole and lining after the same have been thrust through the opening, a wall portion connecting the member and the base, said wall being positioned to engage a marginal edge portion of the sock lining as it is moved from the opening to the base portion and fold it angularly with respect to the sole, said

wall portion being collapsible inwardly, and means for moving the member toward the base portion to cause said wall portion to collapse inwardly and fold down the marginal edge portion 5 of the sock-lining against one of the faces of the sole.

2. In an apparatus of the character described, a plate provided with an opening through which a sole and an attached lining is adapted to be thrust, a base member adapted to receive the sole and lining after the same have been thrust 10 through the opening, means extending around the opening and situated between the plate and base member for upstanding a marginal edge portion on the lining when the sole and lining are moved toward the base member, said means comprising flexible elements moved inwardly in a direction 15 toward the center of the sole when the same is resting against the base member to press down the marginal edge portion against the sole, and means 20 for causing said flexible elements to be moved inwardly upon movement of the plate toward the base member.

3. In an apparatus of the character described, a 25 pair of spaced plates, one of said plates being apertured to permit of the passage of a sole and attached lining through it to reach the second plate, and a plurality of articulated members connecting the two plates and mounted for inward collapse to fold the marginal edge of the lining over the sole and cause it to be adhesively attached thereto, when one of the plates is moved toward the other, and means for moving one of said plates toward the other plate.

35 4. In an apparatus of the character described, a plate provided with a foot-shaped opening through which a sole and an attached lining is adapted to be thrust, a base member adapted to receive the sole and lining after the same have 40 been thrust through the opening, articulated means extending around the opening and situated between the plate and base member to form a wall surrounding the opening for upstanding a marginal edge portion on the lining when the sole and lining are moved toward the base member, 45 and are surrounded by said wall, said means comprising articulated elements moved inwardly in a direction toward the center of the sole while the sole is resting against the base member to press 50 down the marginal edge portion of the lining against a face of the sole to adhesively attach it thereto, and means for causing said flexible elements to be moved inwardly upon movement of the plate toward the base member.

55 5. In an apparatus of the character described, a pair of spaced plates, resilient means for holding said plates in spaced relationship, one of said plates being provided with an aperture shaped to permit of the passage of a sole and attached lining 60 through it to reach a position of rest against the second plate, a plurality of articulated members connecting the two plates and forming a wall conforming in shape to the shape of the sole, said members being mounted for inward collapse to 65 engage over and fold down the entire marginal edge of the lining over the edge of the sole and cause it to be adhesively attached to a face of the sole when one of the plates is moved toward the other plate, and means for moving one of the 70 plates toward the other to cause the inward collapse of said articulated members.

6. In an apparatus of the character described, a plate provided with a foot-shaped opening through which a sole and an attached lining is 75 adapted to be thrust, a second plate situated be-

low and spaced from the first plate and adapted to receive the sole and lining after the same have been thrust through the opening in the first plate, springs for normally holding the plates in spaced relation, a wall portion extending between and connecting the two plates, said wall portion having an inner surface defining a shape similar to the shape of the opening and adapted to fold a marginal edge portion of the lining to an upstanding position when the sole and lining is 10 moved within the confines of said wall on its movement from one plate to the other, said wall portion being flexible to permit of movement of one of the plates toward the other and being constructed to collapse inwardly upon such movement of the movable plate, to overlie and fold down the upstanding edge portion of the lining over the edge and against a face of the sole to adhesively attach it thereto, and means for moving one of the plates toward the other to cause 15 said wall portion to be collapsed.

7. In an apparatus of the character described, an apertured member through which a sole and lining are thrust, a supporting base for receiving the sole and lining after they have been thrust 20 through the apertured member, a collapsible wall connecting the apertured member and supporting base and extending around the aperture, and means for collapsing the wall inwardly upon movement of the apertured member toward the 25 base, to cause a portion of the collapsed wall to overlie the sole and lining resting against the base.

8. In an apparatus of the character described, an apertured element, a base member spaced 30 therefrom, resilient means for holding the apertured element and base member in spaced relation, a resilient wall member extending around the aperture in the apertured element and conforming in shape thereto and extending between 35 the apertured element and the base member, means for forcing a sole and a lining through the aperture to a position of rest on the base member, and means for moving the apertured element toward the base member to collapse the resilient 40 wall portion inwardly in a direction toward the center of the sole resting on the base member and cause the collapsed wall portion to fold a portion 45 of the lining over the sole for the entire periphery of the sole.

9. In an apparatus of the character described, a plate formed with a foot-shaped opening closely conforming to the shape of a sole and a lining thrust through the same, a base plate upon which the lining and sole is brought to rest after having 50 passed through said opening, a wall extending around the edge of the opening and extending between the under side of the perforated plate and the top of the base plate, said wall being composed of a plurality of closely situated collapsible elements adapted when collapsed to have portions extended inwardly in a direction toward the center of the sole resting on the base plate and surrounded by said wall, means for forcing the sole and lining through the opening, and means for moving the apertured plate toward the 55 base plate to collapse the wall and cause it to fold a portion of the lining over the sole.

10. In an apparatus of the character described, an apertured member through which a sole and 60 lining are thrust, a supporting base for receiving the sole and lining after they have been thrust through the apertured member, a collapsible wall connecting the apertured member and supporting base and extending around the aperture, said 65

wall being composed of a plurality of adjacent resilient tubular members capable of flattening under pressure to cause portions of them to project inwardly over the edge portion of the sole 5 and lining and flatten the marginal edge of the lining down upon the sole resting on the base, and means for moving the apertured member toward the base to flatten said tubular members.

11. In an apparatus of the character described, 10 an apertured member through which a sole and lining are thrust, a supporting base for receiving the sole and lining after they have been thrust through the apertured member, a collapsible wall connecting the apertured member and supporting 15 base and extending around the aperture, and means for collapsing the wall inwardly upon movement of the apertured member toward the base, to cause a portion of the collapsed wall to 20 overlie the sole and lining resting against the base, said means comprising a plunger brought into contact with the apertured member, said plunger being provided with an element for forcing the sole and lining through the apertured member before contacting with said member to 25 force it toward the base member.

12. In an apparatus of the character described, 30 an apertured member through which a sole and lining are thrust, a base member on which said sole and lining are brought to rest after having been thrust through the aperture in the apertured member, a collapsible wall surrounding the aperture and conforming in shape thereto and disposed between the apertured member and the base member, whereby the marginal edge of the

lining thrust through the opening will be folded to upstanding position by contact with said wall, a plunger having a portion movable through the aperture for forcing the sole and lining into contact with the base member, said plunger also having a portion for contacting with the apertured member to force the same toward the base member after the first portion of said plunger has brought the sole and lining to rest against said base member, and connections between the apertured member and the collapsible wall whereby said wall will collapse inwardly in a direction toward the center of the sole and lining to fold an edge portion of the lining down upon a face of the sole when the apertured member is moved 15 by the plunger toward the base member.

13. In an apparatus of the character described, 20 an apertured member through which a sole and an attached sock-lining are thrust, a supporting base for receiving the sole and lining after they have been thrust through the apertured member, said supporting base including a normally tilted portion against which the sole and sock-lining are brought to rest and which upon impingement with said tilted portion bring it out of tilted 25 position and hold it in supporting position, a collapsible wall connecting the apertured member and the supporting base and mounted for inward collapse upon movement of the apertured member toward the base member, to cause a portion of the collapsed wall to overlie the sole and lining resting against the base.
